UNITED STATES PATENT OFFICE.

ALVIN RALPH SWAINE, OF DES MOINES, IOWA.

HYDROCARBON-LAMP.

1,028,977.

Specification of Letters Patent. Patented June 11, 1912.

Application filed October 1, 1909. Serial No. 520,499.

To all whom it may concern:

Be it known that I, ALVIN RALPH SWAINE, a citizen of the United States, residing at Des Moines, in the county of Polk and State 5 of Iowa, have invented a certain new and useful Hydrocarbon-Lamp, of which the following is a specification.

My improved lamp belongs to that class of gasolene lamps in which gasolene is delivered to the lamp through a pipe, the generating of gas being accomplished by means of the heat derived from the lamp.

The object of my invention is to provide a lamp of simple, durable and inexpensive 15 construction, especially designed for use in lighting by means of gasolene.

More specifically, it is my object to provide an improved filtering device for the gasolene, so arranged that it will not become 20 readily clogged, and also so arranged that the filter proper may be quickly and easily detached from the lamp for purposes of cleaning, repair or replacement.

A further object is to provide an improved 25 feed valve device for controlling the flow of gasolene.

A further object is to provide an improved fitting for supporting two inverted gas mantles and for supplying air and gas to the 30 lamp, and also, in this connection, to provide a generating chamber for the gasolene extended through the central portion of said fitting to thereby have the heat from the gas mantles applied to said generating chamber 35 in a direct manner to facilitate the generating of gas.

A further object is to provide a gas light of this kind especially adapted to be easily and readily contained within a suitable 40 globe or lamp shade, and further, in this connection, to provide improved means for supporting a lamp shade and heat deflector from the supporting device.

A further object is to provide a gas lamp 45 of this kind in which all of the parts may be quickly, readily and easily assembled or detached for purposes of repair or replacement.

My invention consists in the construction, 50 arrangement, and combination of the various parts of the lamp whereby the objects contemplated are attained, as hereinafter more fully set forth, pointed out in my claims, and illustrated in the accompanying drawings, 55 in which—

Figure 1 shows a side elevation of a lamp

embodying my invention, with part of the shade broken away to show certain details of construction. Fig. 2 shows a central, detail, sectional view of a lamp embodying my 60 invention with the shade and mantle detached. Fig. 3 shows an enlarged, detail, sectional view illustrating the supporting bracket for the lamp and the discharge end of the filtering tube. Fig. 4 shows a side 65 view illustrating the fitting for supporting two mantles and the generating tube. Fig. 5 shows an inverted, plan view of same. Fig. 6 shows an enlarged, detail, sectional view illustrating the filtering device used 70 in the filtering tube and the generating tube, and Fig. 7 shows a detail, edge view of the fitting that supports the various parts of the lamp.

Referring to the accompanying drawings, 75 I have used the reference numeral 10 to indicate a gasolene supply pipe connected with a tank or other suitable source of supply. This pipe is admitted into a union fitting 11 in which is a gasolene supply pipe 12 80 communicating with the pipe 10 and made detachable from it by means of said union. At the lower end of the pipe 12 is a second union fitting 13 connected to a supporting block 14. This supporting block 14 is held 85 in position by means of a bracket 15, designed to be secured to a support such, for instance, as the ceiling of a building, and screwed into said support is a large pipe 16 surrounding the pipe 12 and having its 90 lower end screwed to a fitting 17, which fitting is open on its opposite sides as shown in Fig. 7, and which is screwed at its lower end to the supporting block 14. In this way, the said supporting block 14 is firmly held 95 in position and the operator may have free access to the union fitting 13, so that the supporting block and the rest of the lamp may be readily, quickly and easily detached from the fitting 17 and the pipe 12. Fixed 100 to the supporting block 14 is a series of outwardly extended rods 18, which rods support a metal collar 19, and said collar is adapted to receive and support a lamp shade 20. There is a shoulder on top of the supporting block 14 designed to receive a deflector 21, as shown in Fig. 3, the deflector proper being shown in Fig. 1.

The supporting block 14 has a screw threaded opening extended through it horizontally and the passageway 22 leading from said opening to the top of the supporting 110

block. In one end of said opening, the pipe 23 is screwed, and the other end of said opening is filled by a screw-threaded plug 24 which may be readily and easily removed to provide access to the adjacent open end of the pipe 23. The other end of said pipe 23 is screwed into a valve casing 25 and communicates with the hollow interior thereof. Contained within the filtering pipe 23 is a filtering device which comprises a number of straight, round rods, preferably three, indicated by the numeral 26; and surrounding these rods is a tube of asbestos or other porous material 27, the ends of which extend beyond the rods 26, and each end is closed by means of a wire 28, the asbestos being of such size as to completely fill and loosely fit into the interior of the pipe 23. The advantage of having a number of rods pass through the asbestos tube is that the rods will hold the tube in position against the interior of the pipe and form longitudinal passageways around said rods. This is clearly illustrated in Fig. 6 of the drawings. The said filtering device may, at any time, be readily and easily withdrawn by first removing the screw plug 24 and then grasping the adjacent end of the filtering device with a small pair of pincers so that in the event the filtering device should become clogged or stopped up, it may be removed for cleaning or repairing purposes.

For regulating the flow of gasoline to the generating chamber, I have provided a valve stem 29 screwed into the lower end of the valve chamber 25, and having a needle point 30 to enter a reduced passageway 31 leading upwardly from the hollow interior of the valve chamber. A fitting 32 is screwed onto the lower end of the valve chamber 25 and is provided with a central partition 33 having an opening to receive the valve stem and also having a supporting pipe 34 screwed into its lower end. On the lower end of said pipe 34 is a screw plug 35 having an opening through it for the valve stem 29. A handle 36 is fixed to the lower end of the valve stem. Formed on the valve stem 29 above the partition 33 is a collar 37 so arranged that when the valve stem is screwed down it will strike said partition and limit the downward movement of the valve stem. By means of this construction, it is obvious that the valve stem is strengthened and supported by the tube 34 and that the valve stem cannot be unscrewed far enough to be wholly withdrawn from the valve casing; and the said fitting 32 also provides a chamber to receive packing material to prevent a leakage of gasoline downwardly around the valve stem.

The generating and mantle supporting devices are connected with each other and supported by means of a rod 38 which is screwed into the lower end of the supporting block 14, and which has its lower end screwed to

the mantle supporting fitting. This fitting is preferably formed complete of a single piece of cast metal and it comprises a hollow body portion 39 having two internally screw-threaded extensions 40, extending downwardly. In each of these extensions is a slotted plate 41 for spreading and distributing the mixed gas and air and for preventing the ignition of the gas above them. In the central portion of the fitting 39 is a solid partition 42 having a horizontally arranged opening extended through it. This opening is intersected by set-screws 43. The gas mantles 44 are connected with the extensions 40 in the ordinary manner.

My improved generating device comprises a generating tube 45 extended through the opening in the partition 42 and having arranged therein a number of rods 46, and an asbestos tube 47 arranged in the same manner as the filtering device, as before described. The said tube 45 is firmly held in place by the set-screw 43. At one end of the tube 45 is a hollow fitting 48 screwed to the tube 45 and having a hollow plug 49 screwed into its upper portion to communicate with the interior thereof, and applied to the plug 49 is a union 50 to connect the gasoline supply pipe 51 with the plug 49. This gasoline supply pipe 51 communicates with the top of the valve chamber 25 to which it is held by means of a union 52. The opposite end of the generating tube 45 is screwed into a block 53 which block is provided with a chamber 54, and a small passageway 55 communicates between the tube 45 and the chamber 54. Fitted in one end of the passageway 55 is a short tube 56 having tapered ends, one of which is designed to enter the block 53 adjacent to the upper end of the passageway 55. Mounted within the chamber 54 is an expansion tube for the gas, indicated by the numeral 57. This tube has an opening therein designed to receive the tapered upper end of the small tube 56, and the tubes 56 and 57 are held in proper position by means of a set-screw 58. The outer end of the tube 57 is closed by a screw plug 59 and the other end has a reduced opening 60. A short pipe section 61 is screwed to the block 53 to communicate with the interior of the chamber 54 thereof. This tube is provided with a number of openings 62 in its sides and it is connected by means of a second tube 63 with the part 39.

In practical operation, it is obvious that the device may be quickly and easily assembled as all of the parts are fitted together with screw joints and the entire device is very simple and inexpensive in construction. The generating and burning parts are of compact form and can be readily and easily placed inside an ordinary globe or shade, and the controlling valve 130

stem may be placed at any desired point spaced apart from the side of the globe. The gasolene that enters from the supply pipe 10 flows first through the filtering device, which filtering device is of such construction that it will not readily and easily be clogged; and, if by any reason, it should become clogged up, it may be removed and cleaned by simply removing the plug 24. 5
 10 The needle valve for controlling the flow of gasolene is so arranged that the valve stem may be made of any desired length and it is strengthened and braced by means of the tube 34. Furthermore, all danger of 15 unscrewing the valve to such an extent as to cause leakage of gasolene is prevented by the partition 33 and the collar 37. By placing the generating chamber in a tube, which tube is contained between and above 20 the two gas mantles, I apply a maximum amount of heat to the generator to quickly convert the gasolene into gas. The means for conducting gas to the fitting that supports the burners is also of simple construction 25 and any of the parts thereof may be readily removed or replaced.

I claim as my invention:

1. In a hydrocarbon lamp, the combination of a suitably supported block provided 30 with a chamber adapted to communicate with a source of fuel supply, a filtering pipe extending horizontally from said block, a rod extending vertically from said block, a hollow burner fitting having a pair of downwardly projecting arms, a generating tube 35 extending horizontally between said arms, a connection between said pipe and one end of said tube for supplying liquid fuel to the tube, and means for conducting the vaporized fuel from the other end of said tube 40 into said burner fitting.

2. In a hydrocarbon lamp, the combination of a suitably supported block provided with a chamber adapted to communicate 45 with a source of fuel supply, a filtering pipe extending horizontally from said block, a plug screwed into said block opposite said pipe and in alignment therewith, a rod extending vertically from said block, a hollow 50 burner fitting having a pair of downwardly projecting arms, a generating tube extending horizontally between said arms, a connection between said pipe and one end of said tube for supplying liquid fuel to the 55 tube, and means for conducting the vaporized fuel from the other end of said tube into said burner fitting.

3. In a hydrocarbon lamp, the combination of an open ended tube, a device mounted 60 in the tube comprising a series or number of straight rods and a flexible, porous

tube surrounding them, so as to leave a space between the tube and the rods, and means for supplying hydrocarbon to one end of the tube. 65

4. In a hydrocarbon lamp, the combination of an open ended tube, a device mounted in the tube comprising a series or number of straight rods, and a flexible, porous tube surrounding them, so as to leave a space 70 between the tube and the rods, the ends of said porous tube being closed beyond the ends of said rods, and means for supplying hydrocarbon to one end of the tube. 75

5. In a hydrocarbon lamp, the combination of a suitably supported block provided with a chamber adapted to communicate with a source of fuel, a filtering pipe extending horizontally from said block, a valve casing at the free end of said pipe, a valve 80 in said casing, a handle rod depending from said casing for controlling said valve, a rod extending vertically from said block, a hollow burner fitting having a pair of downwardly projecting arms, a generating tube 85 extending horizontally between said arms, a connection between said casing and one end of said tube for supplying liquid fuel to the tube, and means for conducting the vaporized fuel from the other end of said tube 90 into said burner fitting.

6. In a hydrocarbon lamp, the combination of a burner fitting, a generating tube supported by said fitting, a mixing tube connected at one end to said fitting, a block 95 connecting the adjacent ends of said tubes, said block being provided with an opening into which the mixing tube extends and with a restricted passage-way which communicates with the generating tube, a hollow cylindrical member removably secured in said opening and adapted to establish communication between said tubes, and means for supplying liquid fuel to said generating tube. 100 105

7. In a hydrocarbon lamp, the combination of a filtering chamber, a valve fitting in communication therewith and having a passageway in its upper portion, a needle valve stem screwed into the lower portion of the valve casing, said stem having a fixed collar thereon, a fitting screwed to the lower end of the valve casing and having a partition therein through which the valve stem is extended, said partition being arranged to 110 limit the downward movement of the valve stem by engaging said collar thereon. 115

Des Moines, Iowa, August 3, 1909.
